United States Patent Office

Des. 185,460
Patented June 9, 1959

185,460

WHEEL COVER

Frederic P. Plotkin, Los Angeles, Calif.

Application February 2, 1959, Serial No. 54,406

Term of patent 14 years

(Cl. D14—30)

Fig. 1 is a front view of a wheel cover showing my new design;

Fig. 2 is a cross-section taken along the line of 2—2 of Fig. 1; and

Fig. 3 is a perspective view of the wheel cover shown in Fig. 1.

The fragmentary portion of the mounting ring shown in Fig. 2 is for illustrative purposes only.

I claim:

The ornamental design for a wheel cover, substantially as shown and described.
